DIES FOR FORMING REFERENCE SURFACES
ON ARTICLES CIRCULAR IN CROSS-SEC-
TIONSCarl Herzog, Belleville, N. J., assignor to Western
Electric Company, Incorporated, New York,
N. Y., a corporation of New York

Application April 5, 1949, Serial No. 85,612

1 Claim. (Cl. 78—61)

1

This invention relates to dies for forming reference surfaces on articles circular in cross-section, and more particularly for forming contacts whereby they may be mounted accurately in electrical units.

Certain electrical units employed in the communication arts include contacts which must be accurately positioned with respect to each other and with respect to the centerline of the unit in which they are disposed so that the unit may function efficiently. One form of such units is a mercury switch including pairs of contacts which are to be electrically engaged by a switch element requiring accurate positioning of the contacts relative to each other in their respective pairs and relative to the switch member so that the switch may function properly. The contacts are usually formed of certain types of wire circular in cross-section having smaller portions of precious metal welded thereon to be engaged by the switch member during operation of the switch. The presence of the portion of precious metal on each contact adds to the difficulty of mounting the contacts in the electrical unit so that these portions of precious metal may be positioned for engagement with the switch element.

An object of the present invention is to provide a die which is simple in structure, readily actuatable and highly efficient in forming reference surfaces on an article circular in cross-section.

With this and other objects in view, the invention comprises a die for forming reference surfaces on an article circular in cross-section, the die including a fixed die member having a cavity to receive the article and a second die member having a cavity to cooperate with the cavity of the fixed die member to form reference surfaces on the article which are parallel with the centerline of the article.

More specifically the die members are so formed that two sets of reference surfaces are formed on the article, the first set lying in a given plane with the centerline of the article, while the other set includes parallel reference surfaces spaced equal distances from the centerline of the article and at right angles to their respective first reference surfaces. The second die member is also formed to cause the portion of precious metal welded to the article or contact to be formed so that its outermost surface will be a given distance from the plane including the first reference surfaces and the centerline of the article. A stop member, in the form of a rod, adjustably carried by a holder and extending into the cavity of the fixed die member varied dis-

tances depending upon the desired length of the reference surfaces may be secured at any selected position in a holder therefor, secured to the fixed die member.

5 Other objects and advantages will be apparent from the following detailed description when considered in conjunction with the accompanying drawing, wherein

Fig. 1 is a side elevational view of the die, portions thereof being broken away;

Fig. 2 is a vertical sectional view taken substantially along the line 2—2 of Fig. 1;

Fig. 3 is a fragmentary isometric view of a portion of an article or contact to be formed by the die;

Fig. 4 is a top plan view of the article after it has been formed by the die; and

Fig. 5 is a sectional view taken along the line 5—5 of Fig. 4.

20 Referring now to the drawing, the die includes a fixed die member 10 having a cavity 11 extending the full length of the die member. The die member 10 is secured to the side or aligning members 12 by machine screws 14, these members being mounted with the die member upon a mounting plate 15 by suitable means (not shown). The mounting plate 15 is secured to the bed 16 of a conventional press having a reciprocable ram 17 operable in single cycles by suitable means (not shown). A second die member 20, is supported by the ram 17 for movement relative to its companion die member 10 between the side or aligning members 12. A cavity 21 is formed in the under surface of the die member 20 for the full length thereof, cooperating with the cavity 11 to form the article shown in Fig. 3 into the contour illustrated in Figs. 4 and 5. A stop 23 in the form of a rod extends through an aperture 24 in a holder 25 mounted on the back surfaces of the members 12 whereby the rod or stop 23 may be located at any desired position within the cavity 10 and held in place by a set screw 26 to limit the distance an article 26 extends into the die cavity.

45 In the present embodiment of the invention, the article 26 is a metal structure in the form of a contact wire, circular in cross-section and having a portion 27 of precious metal welded to the periphery thereof, a given distance from the leading end 28 of the article.

During operation of the die, the ram 17 with the die member 20 is reciprocated through operating cycles, each time an article 26 is placed in the die cavity 11. As previously stated, the 55 distance the article or contact extends into the

die cavity 11 is determined by the stop 23. When the die is closed on the article 26 with the portion 27 disposed on the uppermost portion of the article in the die cavity 11, two sets of reference surfaces 30 and 31 are formed on the article. The first set of reference surfaces 30 will be in a given plane with the centerline of the article whereby the utilization of a holder for the mounting of the article or contact in an electrical unit, and it will be known that a surface of the holder contacting the reference surface 30 will lie in a plane with the centerline of the article. The reference surfaces 31 will be formed at right angles to their respective reference surfaces 30 equal distances from the centerline of the article. With the two sets of reference surfaces 30 and 31, it is possible to accurately locate the contact or article within a unit of which it is to be a part. It will also be noted that the cavity 21 is formed whereby the portion 27 of precious metal will be formed simultaneously with the forming of the reference surfaces 30 and 31 to cause the outermost surface 33 thereof to be located a known distance from the plane of the reference surface 30.

It is to be understood that the above described arrangements are simply illustrative of the application of the principles of the invention. Numerous other arrangements may be readily devised by those skilled in the art which will embody the principles of the invention and fall within the spirit and scope thereof.

What is claimed is:

In a die for forming reference surfaces on a cylindrical conductor and precious metal contact carried at a point on the periphery thereof, a first flat die member having a longitudinal cavity substantially semicylindrical in cross-section and having longitudinal recesses at the edges of the said cavity and terminating in the flat face of the die member, which flat face coincides with the center of the circular conductor when placed in the cavity, a second die member hav-

ing a flat face parallel to the flat face of the first die member and also having an inverted U-shaped longitudinal cavity parallel to and narrower than the cavity of the first die member, the sides of the U-shaped cavity being perpendicular and spaced equal distances from the center of the circular conductor when in the die members to shear and forge the sides of said cylindrical conductor to form flat side reference surfaces substantially in the plane of the meeting point of the die members and through the center of said conductor, said inverted U-shaped cavity having a depth to clear the exposed portion of said conductor located between the portions that are sheared and forged and to clear the lower sides of said contact, the bottom of said U-shaped cavity having a contoured surface for engaging and working the top surface of the precious metal contact, and means to cause relative movement of the die members to engage the conductor and the precious metal thereon to form an electrical contact unit having two spaced right angled pairs of reference surfaces and an outer reference surface on the precious metal, all of said surfaces being at predetermined fixed distances from the said center of the conductor.
